UNITED STATES PATENT OFFICE.

WILLIAM A. JOHNSTON AND ARTHUR W. BROWNE, OF PRINCE BAY, NEW YORK, AND
FREDERICK L. WALLACE, OF PHILADELPHIA, PENNSYLVANIA, ASSIGNEES TO THE
S. S. WHITE DENTAL MANUFACTURING COMPANY, OF PHILADELPHIA, PENNSYLVANIA,
A CORPORATION OF PENNSYLVANIA.

ANESTHETIC-ADMINISTERING APPARATUS.

1,340,448.

Specification of Letters Patent.

Patented May 18, 1920.

Original application filed October 7, 1913, Serial No. 795,699. Divided and this application filed September 7, 1918. Serial No. 252,988.

To all whom it may concern:

Be it known that we, WILLIAM A. JOHNSTON and ARTHUR W. BROWNE, citizens of the United States, residing at Prince Bay, 5 county of Richmond, State of New York, and FREDERICK L. WALLACE, a citizen of the United States, residing at Philadelphia, county of Philadelphia, State of Pennsylvania, have invented certain new and use- 10 ful Improvements in Anesthetic-Administering Apparatus, whereof the following is a specification, reference being had to the accompanying drawings.

This invention relates to that class of de- 15 vices which are adapted to be employed by dentists, surgeons, physicians, and other anesthetists in producing and administering anesthetic mixtures in gaseous forms, and is a division of our prior application 20 Serial #795,699, filed October 7, 1913.

The principal objects of this invention are to provide a simple, efficient and durable apparatus which may be readily controlled by the operator to produce an accurate mixture of different gases in predetermined 25 proportions, and be varied as desired to form anesthetics for producing different degrees of anesthesia, and to infuse ether or other volatile liquid anesthetic into the 30 gas passing to the patient.

Other objects of our invention are to provide an anesthetic administering apparatus with means to reduce the respective gases to a predetermined pressure without 35 freezing prior to injecting the volatilized liquid anesthetic therewith, and to provide means actuated by the respective gases to visually indicate to the operator that the gas is flowing or to similarly indicate any 40 cessation in such flow.

Specifically stated, the form of our invention as hereinafter described, comprises an anesthetic administering apparatus having means for delivering nitrous oxid gas 45 and oxygen gas from separate containers into a mixing chamber having an outlet arranged to deliver the proper mixture of gases to the patient through a suitable inhaler, and comprises a flexible gasometer 50 arranged to receive the surplus gas which is not taken by the patient during alter-

nate pulsations of respiration, and also comprehends an attachment which may be interposed between the mixing chamber and inhaler to infuse into the mixture of nitrous oxid and oxygen gases a vaporizing 55 fluid such as ether, for producing different effects upon the patient, such for instance, as profound anesthesia to effect a more complete relaxation of the muscles.

Our invention also includes all of the va- 60 rious novel features of construction and arrangement as hereinafter more definitely specified.

In the accompanying drawings, Figure 1 is a side elevational view of an anes- 65 thetic administering apparatus conveniently embodying this invention, showing two gas cylinders supported by the head of said apparatus, and having a delivery tube provided with an elastic gasometer for sup- 70 plying a mixture of nitrous oxid and oxy- 75 gen gases to the patient; Fig. 2 is a vertical longitudinal sectional view taken axially through the etherizing mechanism and mixing chamber, showing how it may be connected with said mixing chamber and substituted for the delivery tube shown in Fig. 1; Fig. 3 is a vertical transverse sectional view of said etherizing mechanism taken on the line 3—3 in Fig. 2; Fig. 4 80 is a plan sectional view of the mechanism shown in Figs. 2 and 3 taken on the line 4—4 in Fig. 2; and Fig. 5 is a perspective view of the reticulated volatilizing cylinder, *per se*. 85

In said figures the base 1 is divided centrally and comprises four feet, 2, respectively provided with casters 3, and the separable parts of said base 1 being joined together and clamped to the standard 5 by 90 the bolt 6 and wing nut 7, as shown in Fig. 1.

The standard 5 conveniently supports the head 8 which is provided with extensions forming yokes 10, arranged to receive 95 and support the gas cylinders 11 and 12.

The gas cylinders are provided with valves having outlets which are connected to suitable passage-ways in the head 8 leading to the inlets of the pressure re- 100 ducers 13 and 14 for the nitrous oxid and

oxygen gases, respectively. Said pressure reducers are respectively provided with radiating flanges 15 and 16 which are arranged to prevent freezing of the gas as 5 its pressure is reduced for delivery to the patient.

Said pressure reducers 13 and 14 are 10 respectively connected by the pipes 17 and 18 with suitably provided passage-ways in the head 8, leading into the mixing chamber 19 and controlled by valves having handles 20 for the respective gases.

Within the mixing chamber 19 a baffle plate 22 is disposed transversely between 15 the opposed inlet openings 23 of the passage-ways leading from the respective pressure reducers 13 and 14, and adjacent to the inlet openings 23 are pivoted indicating members 25 which are arranged to be 20 rocked by the gas flowing into the mixing chamber to indicate to the operator that the gas is flowing; said indicating members 25 being visible through the transparent closure 26 of the mixing chamber 19, which is held in place by the spring ring 27.

The mixing chamber 19 is provided with the outlet 29 arranged to receive one end 30 of the outlet tube 30 in telescoped relation therein. As shown in Fig. 1, said outlet tube 30 forms a T-connection with the dome 32 to which the flexible gasometer 33, preferably formed of rubber, is attached to receive the surplus gas which is not taken 35 by the patient during the alternate pulsations of respiration. In other words, the flexible gasometer 33 provides an auxiliary reservoir for containing a supply of gas from which the patient may draw.

40 As shown in Fig. 1, the outlet tube 30 is conveniently provided with a cleat 35 forming a hook or support upon which the flexible tube 36 connecting the apparatus with a suitable inhaler (not shown) may be supported when not in use. Said flexible tube 36 is connected at one end with the outlet tube 30 by the elbow 37, having one arm in telescopic relation with the flexible tube 36 and the other arm in telescopic relation with 45 the free end of the outlet tube 30.

In cases where more intense anesthesia is desired or where profound anesthesia is required, it is necessary to employ a liquid anesthetic, such as ether, chloroform, etc., 55 and for this purpose we have devised mechanism for infusing into the anesthetic passing from the mixing chamber ether or such anesthetic in a vaporized condition.

The mechanism for infusing liquid anesthetic into the gas, may be conveniently 60 and readily substituted for the outlet tube 30 and its associated parts, and as shown in Figs. 2, 3, 4 and 5 comprises a casing 39 having a tubular projection 40 engaged in telescopic relation with the outlet of the

mixing chamber 19, and provides a tang or projection 41 arranged to enter the slot 42 in the body of the chamber 19 to maintain the casing 39 in upright position.

The casing 39 is provided at one side with 70 a recess 43 formed by extending the wall 45 of the casing 39 inwardly, and said recess is provided with a closure 46 preferably formed of glass and providing a chamber 47 in which the liquid anesthetic may be 75 volatilized by the gases passing therethrough. The closure 46 is suitably cemented to the ring 49 which is in threaded engagement with the casing 39, as shown in Figs. 2 and 4, and is detachably connected with said casing in gas tight relation by 80 means of the gasket 50 interposed between said ring 49 and the seat 51 in the recess 43.

The tube 40 has an extension 52 projecting transversely through the bore of the casing 39, and through the diaphragm 53, closing the lower portion of the opening 55 in the wall 45 of the recess 43, but leaving the aperture 56 for the passage of gas over said diaphragm 53 from the chamber 47 into the 90 bore of the casing 39 as shown by the arrows.

The liquid anesthetic is conveniently contained in the reservoir 57, which is superimposed upon the casing 39 and provided with 95 a closure 58 having the cleat or hook 59 for supporting the flexible tube 60 when not in use.

The liquid anesthetic is admitted to the vaporizing chamber 47 from the reservoir 100 57 through the passage-way 61, as best shown in Fig. 2, which includes the valve seat 62 for the valve plug 63 whose stem 64 is in threaded engagement with the casing 39, and is provided with the knurled thumb-nut 65, 105 by which it may be rotated to open and close the passage-way 61, as best shown in Fig. 3.

The passage-way 61 includes the tubular spout 66 arranged to direct the liquid anesthetic into the outer end of the vaporizing 110 chamber, in which it may collect to any desired depth upon the lower cylindrical wall thereof.

The casing 39 is provided with the outlet tube 67 extending through the side wall 115 thereof below the vaporizing chamber, and may be conveniently connected with the flexible tube 60 by the elbow having one arm 68 in telescopic relation with said tube 60, and the other arm 69 in telescopic relation with 120 the outlet tube 67, as shown in Fig. 2.

The lower end of the casing 39 is enlarged to form a dome 70, having the enlarged rim 71 for the convenient engagement of the flexible gasometer 72, which is similar to the 125 gasometer 33, shown in Fig. 1.

The mechanism thus far described may be employed to administer nitrous oxide and oxygen gases without the liquid anesthetic, the gas passing from the mixing chamber 130

10 through the tube 40 and its extension 52 and through the vaporizing chamber 47 and its aperture 56 into the bore of the casing 39, thence through the outlet tube 67 and 5 the flexible tube 60 to any suitable inhaling device.

When it is desired to infuse the liquid anesthetic into the gas passing through the vaporizing mechanism, the vaporizer is employed which, as best shown in Fig. 5, comprises a reticulated capillary cylinder formed of closely woven wire mesh 73, having its edges overlapped and connected by rivets 74, and provided with a stiffening 10 ring 75 at one end, and at the other end with the disk 76, which latter is provided with an eccentric opening, from which the tubular projection 78 extends, and is arranged to be telescopically engaged within the tubular 15 extension 52. As best shown in Fig. 5, said tubular projection 78 is provided with a longitudinal slot 79, the walls of which are arranged to embrace the projection 80 on the inner surface of the tubular extension 20 52, as shown in Figs. 2 and 4, to insure that the lower portion of the reticulated cylinder will depend into adjacent relation with the bottom of the vaporizing chamber, and consequently into contact with the liquid 25 anesthetic therein contained. Said liquid anesthetic is absorbed by capillary attraction of the woven mesh 73, and atomized by the gas passing therethrough, which gas carries the atomized liquid anesthetic in suspension 30 from the vaporizing mechanism to such inhaling devices as may be employed.

From the foregoing description, it will be seen that nitrous oxid or oxygen gases may be selectively admitted to the mixing chamber as desired, by means of separate controlling valves operated by suitable hand wheels to admit the desired amount of either gas to the mixing chamber, which admission of the gas will be visibly indicated to 40 the operator by the signals in the mixing chamber, so that should any one of the cylinders become exhausted and the flow of gas cease, the signal for that particular gas will immediately return by gravity to its normal 45 position and visibly indicate to the operator that the gas has ceased to flow, so that the operator may immediately replace the exhausted cylinder with one that is charged and thereby prevent possible danger 50 of accident to the patient.

We do not desire to limit our invention to the precise details of construction and arrangement as herein set forth, as it is obvious that various modifications may be made 60 therein without departing from the essential features of our invention as defined in the appended claims.

Having thus described our invention, we claim:—

65 1. An anesthetic administering apparatus

having a passageway for the gaseous anesthetic, and including therein mechanism for infusing a volatile liquid anesthetic into said gaseous anesthetic, comprising a chamber for said liquid anesthetic, and a reticulated 70 cylinder having one side dipping into the liquid and through which cylinder the gas is directed to atomize and absorb the liquid held in said cylinder by capillary attraction.

2. An anesthetic administering apparatus 75 having a passageway for gaseous anesthetic, and including therein mechanism for infusing a liquid anesthetic into said gaseous anesthetic, comprising a chamber for said liquid anesthetic, and a reticulated member 80 in said chamber extending into the bottom thereof through which the gas in said passageway is directed, to volatilize and absorb the liquid anesthetic held in said reticulated member by capillary attraction. 85

3. An anesthetic administering apparatus having a passageway for gaseous anesthetic, and including therein mechanism for infusing into said gaseous anesthetic a volatile liquid anesthetic, comprising a chamber for 90 the liquid anesthetic, a removable reticulated capillary cylinder having one side dipping adjacent to the bottom of said chamber, and forming a volatilizer through which the gaseous anesthetic is directed to absorb the 95 volatilized liquid anesthetic.

4. An anesthetic administering apparatus having a passageway for gaseous anesthetic, and including therein mechanism comprising a reservoir for liquid anesthetic, a chamber for said liquid anesthetic, means for admitting the liquid anesthetic from said reservoir to said chamber, and a reticulated capillary cylinder extending adjacent to the bottom of said chamber, through which the 100 gaseous anesthetic is directed to absorb the 105 volatilized liquid anesthetic.

5. An anesthetic administering apparatus having a passageway for gaseous anesthetic, and including therein mechanism for infusing liquid anesthetic into said gaseous anesthetic, comprising a reservoir for the liquid anesthetic, a subjacent chamber for said liquid anesthetic, means for connecting said reservoir with said chamber, a valve for controlling the flow from said reservoir to said chamber, and a reticulated capillary cylinder forming a portion of the passageway for 110 said gaseous anesthetic and extending into adjacent relation with the bottom of said 115 cylinder. 120

6. An anesthetic administering apparatus having a passageway for gaseous anesthetic, and including therein mechanism for infusing liquid anesthetic into said gaseous anesthetic, comprising a chamber for said liquid anesthetic, a reservoir for said liquid anesthetic superimposed upon said chamber, means including a valve connecting said reservoir with said chamber, and a reticulated 125 130 cylinder

capillary cylinder dipping into adjacent relation with the bottom of said chamber and having an eccentric inlet tube disposed in telescopic relation with the walls of said 5 passageway, and means to prevent rotation of said cylinder with respect to the walls of said passageway.

7. An anesthetic administering apparatus having a passageway for gaseous anesthetic, 10 and including therein mechanism for infusing into said gaseous anesthetic a volatile liquid anesthetic comprising a chamber for the liquid anesthetic, a removable closure for said chamber, and a reticulated capillary 15 cylinder having one side dipping adjacent to the bottom of said chamber, and forming a volatilizer through which the gaseous anesthetic is directed to absorb the volatilized liquid anesthetic.

20 8. An anesthetic administering apparatus having a passageway for the gaseous anesthetic, and including therein mechanism for infusing into said gaseous anesthetic a volatile liquid anesthetic, comprising a chamber

25 having a removable transparent gas-tight closure, and a removable reticulated cylinder within said closure, having one side disposed in adjacent relation to the bottom of said closure, and forming a volatilizer, through which the gaseous anesthetic is directed to absorb the liquid anesthetic.

30 In witness whereof, we have hereunto set our hands the 23rd day of August, A. D., 1918, the 23rd day of August, A. D. 1918, and the 26th day of August, A. D., 1918, re- 35 spectively.
